UNITED STATES PATENT OFFICE.

ALBERT BOARDMAN, OF HAMILTON, ONTARIO, CANADA, ASSIGNOR TO WESTERN ELECTRIC COMPANY, INCORPORATED, OF NEW YORK, N. Y., A CORPORATION OF NEW YORK.

APPARATUS FOR TREATING GLASS.

Application filed December 4, 1919. Serial No. 342,450.

To all whom it may concern:

Be it known that I, ALBERT BOARDMAN, a citizen of the United States, residing at Hamilton, Ontario, Canada, have invented 5 certain new and useful Improvements in Apparatus for Treating Glass, of which the following is a full, clear, concise, and exact description.

This invention relates to an apparatus for 10 uniting metal and glass and particularly to that step in the manufacture of evacuated bulb structures, such as audions, which is concerned with the insertion of wires in the stem or press of the bulb.

15 In manufacturing stems or presses for the bulbs of electric instruments, it is the custom to support a flare within which the lead wires are properly positioned and then to heat a portion of the flare until it is sufficiently softened for the step of forming the press. Just before the formation of the press, an anchor wire is inserted into the softened portion of the flare so that when the press is formed it is sealed in the glass. Machines for performing this operation have heretofore comprised a movable member for projecting the anchor wire into position and jaws operable by the projecting member for forming the press. The relation between the 20 projecting member and jaws is such that when the projecting member has reached its limit of movement, the jaws have also reached their limit of movement. Thus, should a flare be slightly undersize, the 25 jaws may not be effective to form a tight seal.

It is an object of this invention to provide 30 an operable connection between the projecting member and the press forming jaws of such a character that a tight seal will always be produced regardless of the diameter 35 of the flare.

This object is attained by slidably mounting the projecting member in a stationary 40 holder and by providing a resilient member for operating the projecting member. This resilient member is preferably carried by a cross head from which the press operating jaws are operated. Thus, when the 45 jaws are closing the resilient member contacts with the projection member and advances it its full limit before the jaws are closed. Further movement of the jaws to 50 finish the formation of the seal serves merely

to compress the resilient member without 55 affecting the projection member so that regardless of the diameter of the press the jaws may always be sufficiently closed to produce a tight seal.

The machine features embodying the invention and for carrying the method thereof into effect are applicable as a modification of machines of known construction used for the assembly of the wires and the flare, and are so shown in the accompanying drawings, the machine chosen for illustration being one which is used in the manufacture 60 of audions.

In the drawings, Fig. 1 is a plan view of 70 that part of the machine relating to the operating heads and the flame burner; Fig. 2 is an elevation of part of the machine showing one of the assembly heads with the parts in the position they assume at the time the flare is being heated; Fig. 3 is a plan view of 75 Fig. 2; Fig. 4 is an elevation taken in the direction of the arrows shown in Fig. 2; Fig. 5 is an elevation of part of the machine showing the assembly head with its parts 80 in the position they assume at the instant the press is being formed; Fig. 6 is a longitudinal vertical section of part of the machine showing the detailed structure of the die blocks for supporting the flare and the 85 cooperating parts; Fig. 7 is a perspective view of the article produced by this machine; and Fig. 8 is a perspective view of a vacuum tube involving a flare and stem 90 of the type produced by this machine and showing the relation of the flare and stem 95 to the other parts of the tube.

The machine disclosed employs a plurality of assembling heads, for example, five, mounted upon a rotatable support 1 which is formed as a spider and has a hub fitted 95 upon the centering post 2 and radial arms 3 which carry the assembling heads. The sequential operations are concurrently performed at different stations at which the rotation of the support is arrested. Three of these operations involve the heating of the flare and are carried out by blow-pipes 4, the arrangement being such that the intensity of the heat is increased at the successive stations. The assembling heads are rotated 100 at the heating stations by pinions 5, the shafts of which have bearings in a table 6, the latter also serving as the support for the 105

post 2; the pinions 5 are driven by belt gearing from a counter shaft 7.

Each assembling head (Figs. 2-4) is rotatably mounted by means of its shaft 8 in a terminal bearing 9 of one of the arms 3 and includes a bracket 10 mounted on the upper end of said shaft and by which the operating parts are supported. Below the bearing 9, the shaft 8 is provided with a pinion 11 which is actuated by the several pinions 5 at the heating stations. The flare F is supported by cooperating jaws 12 provided at the ends of lever arms 13; these are mounted upon upright rock shafts 14 fitted in bearing lugs 15 formed in the bracket 10. The hub portions of the arms 13 are preferably intergeared as at 16 (see Fig. 3), and the arms are caused to grip the flare by a suitable spring 17 bearing between the finger levers 18 which project from the lower ends of the shaft 14. The wires to be secured in the flare are supported and secured by a die block (Figs. 5 and 6) which consists of an external tubular part 19 adjustably mounted, as by a screw fastening 20, in a collar 21 formed in the bracket 10 and an internal part 22 which is mounted for axial adjustment in the part 19 and is secured by a screw fastening 23. The die block is, of course, located in alignment with the flare and its part 19 has at its upper end a web which is pierced by a row of apertures employed for centering the wires. The lower ends of the leading-in wires engage the part 22 as a support. The press P (Fig. 7) is formed by a pair of opposing jaws 24 which are provided at the free ends of angular levers 25, these being pivoted at their other ends to ears 26 projecting from the collar 21 and being connected by links 27 to an operating head 28 mounted at the upper end of a reciprocating rod 29. The shaft 8 has a central bore in which the rod 29 operates, said rod normally projecting below the pinion 11. When the assembling head is at the last heating station E, the rod 29 will be in alignment with an operating plunger 30 which is movable through an opening in the table 6 and below said table is suitably linked to a pedal 31 (see Fig. 7). The carrier 1 is held against accidental movement from a position in which the several assembling heads are located at the respective stations by a spring-pressed detent 32, mounted on the table 6 and cooperating with a projection 33 carried by the adjacent arm 3. The detent 32 is depressed manually to disengage the projection 33 in order that the carrier 1 may be rotated to bring each assembling head to the next station.

Assuming the flare to be supported by the jaws 12, and the several wires to be in their normal positions of assembly relative to one another and to the flare, the press is formed at the heating stations E by the operation

of the jaws 24 in consequence of the upward movement of the rod 29 and head 28 as effected by the pedal 31.

The machine features above referred to are not new, but have been briefly described in order to facilitate an understanding of the invention.

Referring to Fig. 6, the wire to be projected is the central anchor wire W, and according to the invention, this wire is normally held in a position in which it is not subject to the heat of the flames playing upon the flare and from which it may be directly moved to its normal position of assembly at the time the press is to be formed. In the embodiment disclosed, the wire W, which like each leading-in wire L, is centered in one of the apertures of the part 19 of the die block, is supported on a stem 34 in a position where its lower end is below the flare and preferably below the upper face of the part 19. The stem 34 is movable axially in a central bore in the part 22 and is provided with a collar 35 operating in an enlargement of said bore and which engages a plug or shoulder 36, at the lower end of said enlargement, as a support. The stem 34 is operated to project the wire W into the flare in connection with the operation of the jaws 24, the means employed preferably comprising a spring 37 secured to the head 28 and having a free portion arranged under the stem 34. The lower portion of the stem 34 extends beyond the part 22 and, when the head 28 is raised to effect the operation of the jaws 24, the spring 37 engages the stem 34 and raises it to project the wire W into the flare. This action takes place preferably just before the jaws 24 engage the lower portion of the flare. During the upward movement of the head 28, the overhanging portion of the spring 37 engages the lower end of the part 22 at which time the wire W is fully projected; and thereafter, as the upward movement of the head 28 continues, the arms of the spring are pressed relatively inward. The spring 37 supports the stem 34 in its elevated position throughout the operation of the jaws 24 and thus insures the secure anchorage and accurate centering of the wire W in the press P, as shown in Figure 5. After the press has been formed, the pedal 31 is released whereupon the various parts drop by gravity into their normal positions, as shown in Fig. 4.

The three heating stations C, D and E are located above the table 6; and at one side of said table are the stations A and B in which the flare and the wires are arranged in the assembling head. At station A, an operator removes the unit (Fig. 7) completed at station E and, in preparation for another cycle of operations, places a flare in the jaws 12 and the leading-in wires

L in the appropriate apertures of the die block. At station B, another operator places the wire W in the central aperture of the die block and at stations C, D, and E, the flares are subjected to heat successively and to an increasing degree, the unit being completed at station E in the manner above described.

What is claimed is:

10 1. A machine for treating glass comprising means for supporting a flare of glass, press forming means, means for projecting a wire into said flare, means for operating said press forming means, and means contacting with said operating means and said projecting means whereby one of said means actuates the other, said contacting means allowing relative movement of said operating means and said projecting means.

20 2. In a machine of the character described, supporting means for a flare of glass, press forming means, means for projecting a wire into said flare and resilient means for operating said projecting means by said press forming means and means for operating said press forming means.

30 3. In a machine of the character described, the combination with a supporting means for a flare, press-forming jaws and means for operating said jaws, of a support for a wire, said support being movable to project the wire into the flare, and means on said jaw operating means for actuating the support at the same time the jaws are operated, said actuating means allowing relative movement of said support and said jaw operating means.

40 4. A machine for treating glass comprising means for supporting a flare of glass, means for heating the glass along any desired portion, means for forming a press on said flare, and means operable by said press forming means for projecting a wire into said flare immediately prior to the formation of the press, said projecting means allowing movement of said press forming means relative to said wire.

50 5. A machine for treating glass comprising a flare, a support for a wire to be inserted into said flare, means for forming a press on said flare, means for projecting said wire into the flare and a resilient member carried by said press forming means for operating said projecting means.

55 6. In a machine of the character described, means for supporting a flare of glass, a support for a wire to be inserted into said flare, an operating member, and a resilient member carried by said operating member to engage said wire support.

60 7. In a machine of the character described, means for supporting a glass flare, press forming means, means for projecting a wire into said flare, means for operating said press forming means, and means interposed

between said projecting means and said operating means for communicating movement from said operating means to said projecting means.

8. In a machine of the character described, the combination with supporting means for a flare, press-forming jaws, and means for operating said jaws, of a support for a wire, said support being movable to project the wire into the flare, and resilient means for communicating movement from said jaw operating means to said projecting means.

9. In a machine of the character described, the combination with supporting means for a flare, press-forming jaws, and means for operating said jaws, of movable means for supporting a wire and a resilient member for operating said supporting means to project the wire into the flare, said member being actuated by said jaw-operating means.

10. In a machine of the character described, the combination with supporting means for a flare, press-forming jaws, and means for operating said jaws, of a movable stem for supporting a wire, and resilient means interposed between said jaw operating means and said stem for communicating movement from said operating means to said stem.

11. In a machine of the character described, the combination with supporting means for a flare, press-forming jaws, and means for operating said jaws, said means including a vertically movable element, of a movable stem for supporting a wire, and a spring between said stem and said vertically movable element at a period of the movement of said element, said spring acting to move said stem and thereby project the wire into the flare.

12. In a machine of the character described, the combination with supporting means for a flare, press-forming jaws, means for operating said jaws including a vertically movable element, and a die block arranged below said supporting means and comprising an external tubular part having at its upper end a web pierced with apertures and a second part fitted in said tubular part to provide support for wires arranged in certain of said apertures, of a stem slidably mounted in the second part and projecting below the die block, said stem constituting a support for a wire arranged in one of said apertures and being movable to project the wire into the flare, and a spring contacting with said stem and said element at a period of the operation of said jaw operating means.

In witness whereof, I hereunto subscribe my name this 18th day of November A. D., 1919.

ALBERT BOARDMAN.
